CHILD'S RIDING VEHICLE

Howard J. Morrison, Highland Park, and Marvin I. Glass,
Chicago, Ill., assignors to Marvin Glass & Associates,
Chicago, Ill.

Filed Jan. 29, 1971, Ser. No. 111,175

Term of patent 14 years

Int. Cl. D21—01

U.S. Cl. D34—15

FIG. 1 is a perspective view of the child's riding vehicle showing our new design;

FIG. 2 is a right side elevational view of FIG. 1 on an enlarged scale;

FIG. 3 is a top plan view of FIG. 2;

FIG. 4 is a front elevational view of FIG. 2;

FIG. 5 is a rear elevational view of FIG. 2;

FIG. 6 is a bottom plan view of FIG. 2.

We claim:

The ornamental design for a child's riding vehicle, substantially as shown.
